STRAIGHT BAR KNITTING MACHINE

George Taylor, Daybrook, Arnold, Nottingham,
England, assignor to Allen, Solly & Company,
Limited, Nottingham, England

Application July 30, 1936, Serial No. 93,452
In Great Britain July 31, 1935

16 Claims. (Cl. 66—88)

This invention comprises improvements in straight bar knitting machines and in the production of fabric or articles thereon, the invention having more particular reference to rib knitting machines. The term "straight bar knitting machine" as used in this application refers to a machine in which a line of needles is fixed to a support termed a needle bar for movement in unison, for example, as in machines of the Cotton 10 type. By the expression "straight bar rib machine" is meant one which has two such lines of needles for drawing loops in opposed directions.

Heretofore in the production of hose on the aforesaid type of rib knitting machine it has been 15 customary to knit a blank incorporating the leg or panel and instep along with portions of the heel on said machine and subsequently transfer the blank to a footing machine for the production and attachment of plain (non-rib) heel and toe 20 portions and foot sole; and it is an important object of the present invention to obviate the necessity of employing a footing machine for making plain heels and toes and to enable rib 25 knitted hose with plain (non-rib) heels and toes to be produced on one machine by one and the same knitting process, thereby considerably expediting and cheapening the production of such hose.

Broadly, therefore, the present invention resides 30 in the provision of a rib knitting machine of the straight bar type incorporating means for changing at will from the production of rib fabric to the production of plain (non-rib) fabric or vice versa.

In straight bar rib knitting machines stitch 35 production is effected by relative movement between the needles and other elements of the machine, and the invention, therefore, includes a straight bar rib knitting machine having elements movable in relation to the needles in the production of knitted stitches, and means for effecting differing relative movements between said elements and two simultaneously-knitting groups of needles whereby one group produces rib 40 fabric and the other plain fabric.

The present invention provides a straight bar 45 rib knitting machine having means whereby at predetermined times the needles appertaining to one needle bar or to a predetermined section or 50 sections of said bar are rendered inoperative as stitch-forming elements and the stitches previously produced on said needles are transferred to the needles of the other bar and knitting is continued on said lastnamed needles. By this means, 55 the stitch production can, at any predetermined

time and at a predetermined part or parts of the full width of the fabric being produced, be changed from rib to plain or vice versa, and this enables hose blanks having rib knitted panels and insteps and plain knitted heel and toe portions 5 to be knitted in one process on the same machine.

Insomuch as this invention embodies a process of knitting on a straight bar rib machine a hose blank consisting of leg or panel and instep or foot portion of rib fabric and heel and toe portions (and if desired the sole also) of plain (non-rib) fabric, it will be appreciated that a subsidiary feature of the invention is the provision of means for knitting rib fabric on a group of the needles and for knitting plain fabric simultaneously on a contiguous group. Thus plain fabric may be knitted on the heel needles simultaneously with knitting of rib fabric on the instep needles located between them. Moreover means are provided whereby the two groups knit the 20 same kind of fabric for a predetermined number of courses (as in the leg or panel) and one of them knits rib and the other plain fabric for other courses (as in the instep and heel).

As is well known, on a straight bar rib knitting 25 machine it is customary to employ two sets or rows of needles (frame and machine needles) operating at an angle to each other so as to draw stitch loops in different directions, and in the production of rib fabric other than 1/1 rib certain of the frame needles are provided with long beards and the remainder with short beards, the arrangement and distribution of said long and short beards determining the type of rib produced. Desirably the machine according to the 30 present invention is provided with means for causing needles of one needle bar or set or of a section or sections thereof, during a predetermined number of courses, to cast off the thread fed to them without knitting it, while the opposing 35 needles of the other bar or set knit, and means for causing said needles of both sets to knit at other courses in the production of ribbed fabric. Therefore means may be provided for effecting differing pressing motions according to whether 40 rib or plain fabric is to be produced.

The invention is equally applicable to straight 45 bar machines of the English and German types, the main difference between these two types being that in the English machine the needle-pressing 50 is effected by moving the needles to a stationary presser bar, whereas in the German type the pressing is accomplished by moving the presser bar on to the needles.

In the production of hose, in accordance with 55

the present invention, of rib knitted fabric having plain toe and heel portions in one process on a straight bar machine of either of the two types above-mentioned, it is necessary that means are provided whereby the pressing of the needles of the frame needle bar can be separately controlled for three sections of said bar, i. e. the central or instep section and the two side or heel sections, so that while rib knitted fabric is being produced on the instep section, plain fabric can be simultaneously produced on the heel sections, and also to enable either rib or plain fabric to be produced on the instep section; and it will be appreciated that the means employed for effecting this separate control of the pressing of the needle groups necessarily differs in accordance with the type of machine on which the knitting is to be effected.

In a machine of the English type according to this invention the differing pressing motions (according to whether rib or plain fabric is to be produced) are imparted to the needle bar or sections thereof. In machines of the German type according to this invention they are imparted to the presser bar or sections thereof. In a machine equipped with short bearded needles interspersed with long bearded needles in one needle bar this permits the short bearded needles to knit in the production of plain fabric but to be rendered inoperative in the production of rib fabric.

When the machine is equipped with a divided needle bar means are provided for imparting differing motions to its several sections, and when the machine is provided with a divided movable presser bar differing pressing motions are imparted to its several sections. Moreover means may be provided for imparting said differing motions simultaneously to the several sections, so that rib fabric is produced on the needles appertaining to one section simultaneously with the production of plain fabric on the needles appertaining to another section. Furthermore the said differing motions may at different times be imparted to one and the same section whereby the needles appertaining to that section produce rib fabric at one time and plain fabric at another.

More specifically in the case of a machine equipped with long bearded and short bearded needles as hereinbefore referred to, there may be means causing the short bearded needles to press with the long bearded needles in the production of plain fabric, but for delaying their pressing until after the opposing needles have pressed in the production of rib fabric. Therefore the machinery may be equipped with two alternative presser cams and with means for changing over from one to the other.

In order that the invention may be better understood reference will now be made to the accompanying drawings, in which

Figure 1 shows diagrammatically the set-out of the machine and frame needles of a straight-bar machine for the production of six and three rib.

Figure 2 is an elevation of the relevant parts of an English straight-bar machine according to this invention.

Figure 3 is an elevation looking in the direction of the arrow 3 in Figure 2, of certain of these parts.

Figures 4 to 12 inclusive show the stages in the change over from rib to plain knitting in an English machine according to this invention.

Figure 13 is an elevation of the relevant parts of a German straight-bar machine according to this invention.

Figure 14 is an elevation of certain of said parts looking in the direction of arrow 14 in Figure 5 13, while

Figure 15 is a scrap view of mechanism for moving a group of heelings needles in said machine.

Figure 16 depicts a stocking or like blank produced according to this invention.

Figures 17 and 18 illustrate an arrangement and operation of the frame needles, utilized in the change-over between plain and rib fabric, to obviate the necessity for a divided needle bar or 15 presser.

In the production of ribbed fabric other than 1/1 rib on a straight-bar knitting machine it is customary to employ a full set of frame needles, some of which are provided with long beards and 20 some with short beards. Thus referring to Figure 1 in which the needle arrangement for six and three rib is illustrated the frame needles 10 are arranged in groups of six long bearded needles 10a alternating with groups of two short bearded needles 10b. The machine needles are indicated at 11 and opposite the intervals between the long bearded frame needles there are arranged five dummy machine needles 11a (which are in effect needle shanks without 30 beards) and opposite the intervals between the short bearded frame needles 10b and between said needles and the adjacent long bearded needles 10a there are arranged three bearded machine needles 11b. The thread is laid by a 35 yarn guide 12 across the frame needles 10 and is sunk and divided by sinkers 13. Thereafter the frame needle bar 14 descends to draw the new loops down over the sinker nibs and is rocked forward sufficiently by a cam 15a to press 40 the long bearded needles 10a against the fixed presser bar 16 so that the previously-formed loops are cleared onto the beards. The short bearded frame needles 10b are not pressed, however, until after the loops have been taken 45 under the beards of the machine needles 11b and the latter pressed on the underside of the presser bar 16. Thereupon the frame needle bar moves forward again so that the short bearded needles 10b are pressed and the sinker loops 50 that extend over them between the machine needles 11b are cast off. The beardless machine needles 11a and the short bearded frame needles 10b therefore merely act as dummies and six and three rib is produced.

In applying this invention to the manufacture of a blank for a full fashioned stocking, sock or the like as illustrated in Figure 16 this process is continued until the line 20 at the commencement of the heels is reached, splicing being 60 previously inserted if desired from the diagonal line 21. A change over from rib to plain fabric is thereupon effected on the groups of needles that knit the heel tabs 22. In effecting this change over all the machine needles 11b in said 65 groups are rendered inoperative and the last-formed loops of the rib fabric on them are transferred to the corresponding frame needles on which plain knitting is continued. It is to be noted, however, that while the heel tabs 22 are 70 knitted of plain fabric, the instep portion 23 is still knitted of six and three rib.

It is here to be understood that in transferring rib loops from machine needles 11b to frame needles 10b, said loops are spread from said 75

machine needles to the frame needles, and are not released from the machine needles until such time as the frame needles have been operated to form stitches from said transferred loops.

5 In Figure 4 a rib loop is shown hanging from the machine needle 11b and a plain loop from the long bearded frame needle 10a. These loops form part of the last ribbed course. The machine is stopped, and the rib loop R is transferred as aforesaid from the machine needle 11b to the adjacent short bearded frame needle 10b by a transfer point 30, the requisite number of points being mounted upon a bar and operated by hand or by any desired mechanism.

10 15 This stage is shown in Figure 5, and thereafter, when the machine is started again, the frame needles rise to clear the transferred loops below the beards. At the next course thread is laid across the frame needles and above the machine 20 needles by the guide 12, and the sinkers 13 sink and divide the thread into loops as shown in Figure 6. The frame needle bar 14 descends and moves towards the presser 16 and presses first the long bearded frame needles 10a and then 25 the short bearded ones 10b. After both kinds of frame needles have been pressed (Figures 7 and 8) the frame needle bar descends still further to pull the stitches down (Fig. 9) through the old loops and draw loops of thread over the 30 shanks of the machine needles, and when the frame needle bar has moved forward slightly but not far enough to carry the loops of thread on the machine needles to the landing position the machine needles 11b (which act as dummies) 35 are pressed (Fig. 9). The knocking-over bar 31 then moves forward, Figs. 10, 11 and 12, to discharge the loops from the pressed machine needles and the frame needle bar rises to the next course.

40 It will be appreciated that there is a difference between the sequence of operations for the production of ribbed fabric and plain fabric. In the production of ribbed fabric, in which the short bearded frame needles 10b act as dummies, these needles are not pressed until after the long bearded frame needles and the machine needles have been pressed. This necessitates two separate forward motions of the needle bar 14 for pressing. In the production of plain fabric, in which the short bearded frame needles 10b are operative, the needle bar is held in the pressing position so that these needles are pressed immediately after the long bearded needles have been pressed. As the instep needles are producing ribbed fabric at the same time that the heel needles are producing plain fabric, in a straight-bar machine of the English type in which a fixed presser is used it is necessary to have a divided needle bar so that these two different sequences of pressing operations may be effected on the frame needles. Therefore the frame needle bar 14 is divided into three parts as is shown in Figure 3:—a part 14a which carries the instep needles flanked by parts 14b which carry the heel needles, and means are provided for changing over from one to other of these sequences. On the cam shaft 32 there are two presser cams 15a, 15b co-operating selectively with a truck or cam follower 33 on a pending arm 34 attached to an additional presser shaft 29. This arm is connected through an arm 35 to two arms 36 which depend one from each of the heel portions 14b of the needle bar.

70 It is to be observed that the cam 15a, which is employed when ribbed fabric is to be made on

the heel needles, has a short lobe 37a which maintains the needle bar in the pressing position only for a sufficient time for the long bearded frame needles 10a to be pressed, and another lobe 38 that causes the needle bar subsequently to move forward again to carry the loops on the machine needles 11 to the landing position thereon at which time the needles 11b are in the pressing position, while a further lobe 37 causes the short bearded frame needles 10b to be pressed. On the other hand, the cam 15b which is employed when plain fabric is to be made on the heel needles, has a longer lobe 37b which maintains the needle bar in the pressing position for a period sufficient to ensure that both the long bearded and the short bearded frame needles are pressed (Figs. 7 and 8); another comparatively small lobe 38b functioning to ensure that the loops of thread on the machine needles 11 are not carried to the landing position before the beards of the needles 11b are pressed. At the commencement of change over from rib to plain fabric the truck 33 is moved by a control member 39 (controlled by the chain or other control device) from co-operation with the cam 15a to co-operation with the cam 15b.

75 When the required amount of plain fabric has been produced on the heels, simultaneously with the production of ribbed fabric in the instep, the heels are pressed off, but during their production they may be fashioned by fashioning points 28. Thereafter the machine continues to produce a ribbed instep on the instep needles associated with the portion 14a of the needle bar, but at the termination of the instep portion of the blank it is desirable to make a plain toe. Therefore the machine is again stopped and rib stitches appertaining to the instep are transferred by the transfer points 30 to the frame needles as has been described with reference to the stitches of the heel, and the instep needles are operated to produce plain fabric. For this purpose presser cams 115a and 115b, similar to the cams 15a, 15b, are provided on the cam shaft 32, co-operating with a shiftable truck similar to 33 on an arm 134 attached to the ordinary presser shaft 129. This arm is connected by an arm 135 to an arm 136 depending from the base of the central portion 14a of the needle bar.

80 The toe is shaped in any known or approved manner and the plain heel and toe portions may also be spliced or reinforced. At the termination of the toe the fabric may be pressed off, or alternatively knitting may continue on the central group of needles to produce a plain foot 55 bottom.

85 The application of the invention to a straight-bar machine of the German type will now be described. A feature of distinction between this type of machine and the English machine is that the frame needle bar does not rock to press the needles, but merely rises and falls and a movable presser bar is therefore provided instead of a fixed presser bar. Hence in the German machine according to this invention this presser bar is divided into three portions and means are provided for imparting movements to it.

90 The production of rib fabric on this machine is in the main similar to the production on the English machine, it being remembered that instead of the needle bar rocking forwards to press the frame needles the presser bar 40 is moved towards the needles. This distinction, however involves a further modification in the German machine to permit plain fabric to be produced.

At the stage in the production of rib fabric, corresponding to that shown in Fig. 10, the loop there shown as extending over the beard of the machine needle 11b would extend under the 5 beard, because a rib stitch is to be produced from it. In the English machine this loop is prevented from being enclosed by the beard of the machine 10 needle, by limiting the forward motion of the frame needles while the machine needles are pressed; in the German machine the machine needles of the heel sections (and of the toe section if plain fabric is to be produced in the toe) are thrown forward a short distance (approximately $\frac{1}{4}$ th of an inch) at the change over 15 from rib to plain, so that the loops are positioned beyond the tips of the machine needle beards when these beards are pressed beneath the presser 40 after which the loops are cast off. One 20 construction of mechanism by which this forward movement is imparted to the machine needles is illustrated in Figure 15. The leads or other elements 43 in which the machine needles are mounted in the machine needle bar 42 are slidably mounted on that bar, and above the needle bar there is another bar 44 having oblique slots 25 45 in each of which a pin 46, secured to the adjacent element 43, is positioned. Therefore when the bar 44 is moved endwise over the needle bar 42, as it may be by a lever 47 and a suitable 30 control operated from the pattern chain or the like, the machine needles are projected forward bodily. There may be one such device for the heel needles and another for the instep needles, but actually, it is only necessary for the heel 35 needles to be capable of projection as described with reference to Fig. 15. For the change-over to produce a plain toe the whole machine needle-bar may be projected, for example by shifting the truck on the lever by which the machine needle-bar 42 is operated into engagement with a special 40 cam. This mechanism is not illustrated, for it may in all essentials be similar to that herein-after described and illustrated for modifying the movements of the sections of the frame needle-bar. 45

As on the English machine, during the production of rib fabric the short bearded frame needles are not pressed until after the long bearded frame needles and the machine needles have been 50 pressed and therefore the presser bar 40 of the German machine is given three forward movements, firstly for the pressing of long frame needles, secondly while the machine needles are 55 pressed and thirdly for the pressing of short frame needles. In the production of plain fabric on the German frame, however, two forward motions only are required, the presser bar being maintained in its first pressing position while the frame needle bar 41 descends so that both the 60 long and short bearded frame needles are pressed at the one operation, and the second motion being as before mentioned, the third forward motion not being required. Therefore instead of dividing the needle bar into three parts the presser bar 40 is divided into three parts:—a central 65 part 40a for the instep needles flanked by parts 40b for the heel needles as shown in Figure 14, so that rib and plain fabric may be produced simultaneously. These parts are operated by 70 cams on the cam shaft 58. The part 40a rocks about a shaft 51 and is provided with a depending arm 52 carrying a truck 53. This truck is movable by a control 54, operated from the pattern chain or the like, into engagement with 75 either of two cams 55a, or 55b on the said cam

shaft 58. One of these cams is provided with three lobes for effecting the three distinct pressing movements required for the production of ribbed fabric while the other is provided with one long lobe for effecting the single prolonged advance of the presser necessary for the production of plain fabric, the length of this lobe being such that the presser bar is held in pressing position while the needle bar 41 descends to press the short beards as well as the long ones, a second 10 lobe being provided for effecting the advance of the presser necessary for the pressing of the machine needles. The heel portions 46b of the presser bar rock about a shaft 51 and are provided with a depending lever 52 carrying a movable truck 53. This truck may be moved by a control 54, operated from the pattern chain or the like into engagement with either of two cams 55a or 55b (similar to the cams 55a, 55b) according to whether plain fabric or rib fabric 20 is required.

Therefore in the change-over from rib to plain fabric, be it at the commencement of the heel tabs or at the commencement of the toe, the following operations must be performed:—the machine must be stopped; the rib loops transferred by the points 38 from the bearded machine needles 11b to the corresponding frame needles; the appropriate control, illustrated in Fig. 15, operated to project those machine needles that are 30 to be inoperative and correspond with the group or groups of frame needles on which plain fabric is to be produced; and the appropriate control 54 or 554 operated to change radically the motions of the appropriate section or sections of the 35 presser bar 40. Thereafter plain fabric is produced substantially as has been described with reference to Figs. 4-12, with this chief distinction, that instead of the frame needles moving towards the presser 46 for pressing, the presser 40 moves towards the frame needles.

The transfer bars required for transferring the machine needle stitches of the heels and the machine needle stitches of the instep will, of course, require to have their points distributed 45 and arranged in accordance with the stitches to be transferred; the transfer bar for transferring the machine needle stitches of the heels having its points arranged in two spaced groups, each group appertaining to a heel and the space there-between coinciding with the instep needles which 50 do not require to be operated upon.

As has been explained, during the production of plain fabric the long and short bearded frame needles press substantially simultaneously, while 55 in the production of rib fabric the short bearded needles press after the long bearded needles. In order that these different pressing operations may be effected simultaneously on different sections of the needle-bar, the English machine has 60 been described as having a divided needle-bar and the German machine as having a divided presser bar. If, however, the two kinds of frame needles are movable longitudinally the one in relation to the other so that the beards of the 65 needles 10b may be brought level with the beards of the long-bearded needles 10a (as in Fig. 18) both kinds of frame needles may be pressed simultaneously in the production of plain fabric. Any suitable means (for example similar to that 70 described with reference to Fig. 15) may be employed for moving the short bearded frame needles 10b between the positions shown in Figs. 17 and 18 at the change-over between rib and plain. Such movements may be applied to the 75

short bearded needles in the heel or toe sections, or may at different times be applied to the needles in both said sections.

- In one arrangement, prior to the descent of the 5 needle bar during the production of plain fabric, the short-bearded needles are lowered somewhat to bring them to the relative position shown in Fig. 18, while when the needle bar descends they are restored to the position shown in Fig. 18.
- 10 Relative movement between the two kinds of frame needles may be applied to the English machine (to obviate the necessity for a divided needle bar) or to the German machine (to obviate the necessity for a divided presser bar) but 15 is particularly applicable to the latter. In such an application of this modification, only the short-bearded heel needles are displaceable downwards, and in making plain fabric on the toe needles the whole machine needle-bar is 20 moved forwards (as hereinbefore described) while the undivided presser bar is caused to remain forward until all the needles have pressed. For this purpose the truck on the lever operating the presser may be moved into contact with a 25 special cam.
- Although the invention has been described by way of example applied to a machine for making 6/3 rib fabric, it is to be understood that same is applicable to machines for making other rib fabric including 1/1 rib.
- Consequent upon the foregoing description of the invention as applied to a change over from rib to plain fabric, the application of the invention to a change over from plain to rib fabric 35 will present no difficulties to one skilled in the art, the various change over operations being merely reversed.
- The invention is applicable both to single unit and to multi-division straight-bar machines.
- 40 I claim:
1. A straight bar rib knitting machine having elements movable in relation to the needles in the production of knitted stitches, and means for effecting differing relative movements between said elements and two simultaneously-knitting groups of needles whereby one group produces rib fabric and the other plain fabric.
2. A straight bar rib knitting machine, having means for rendering inoperative as stitch-forming elements at predetermined times needles of 45 one needle bar, means for transferring to opposed needles of the other bar the stitches previously formed on said inoperative needles, and means for continuing to knit on the needles of the other bar.
3. A straight-bar rib knitting machine, having interspersed long and short bearded needles in one needle bar, means for causing the long bearded needles to co-operate with needles in the other bar in the production of rib fabric and for preventing the short bearded needles from knitting, and alternative means for causing said long and short bearded needles to knit plain fabric and for preventing the opposing needles in the other bar 55 from knitting.
4. A straight-bar rib knitting machine organized for the production of ribbed blanks for stockings or the like, having means for knitting a plain heel and a ribbed instep.
5. A machine according to claim 1, having 60 means for knitting the same kind of fabric on both groups simultaneously for a predetermined number of courses and for knitting plain fabric on one and rib fabric on the other group for other courses.
6. A Cotton's patent rib knitting machine having two opposed sets of needles, thread-feeding means for feeding thread thereto, and means for causing the needles to knit said thread, in combination with means for causing needles of one set, during a predetermined number of courses, to cast off the thread fed to them without knitting it, means for causing needles of the other set to knit the thread into plain fabric, and means for causing needles of both sets to knit 10 ribbed fabric at other courses.
7. A straight-bar rib knitting machine having a division of needles for knitting a selvedged blank, which division comprises two sets of opposed needles, and one of which sets includes 15 short bearded needles interspersed with long bearded needles, means for knitting plain fabric on the short and long bearded needles of said one set, means for rendering the short-bearded needles inoperative and for knitting rib fabric 20 on needles of the two sets in co-operation, and means for changing-over at will from one kind of fabric to the other whereby both kinds of fabric are embodied in the same blank.
8. A straight-bar rib knitting machine having 25 a division of needles for knitting a selvedged blank, which division comprises two sets of opposed needles, and one of which sets includes short bearded needles interspersed with long bearded needles, means for knitting rib fabric 30 on long bearded needles of the said one set and needles of the other set, means for rendering the short bearded needles of said one set inoperative as stitch-producing elements during the production of the rib fabric, means for rendering 35 needles of said other set inoperative as stitch-producing elements, and means for producing plain fabric on the long and short bearded needles of said one set.
9. A machine according to claim 8, having 40 means for adjusting the short bearded needles lengthwise of the long bearded needles so that they press together in the production of plain fabric.
10. A Cotton's patent knitting machine, having 45 means for knitting rib or plain fabric at will in the production of a blank in which courses of the one kind follow courses of the other, and means also for knitting both kinds of fabric simultaneously in said blank.
11. A Cotton's patent rib knitting machine, having a divided needle-bar equipped with alternating long and short bearded needles, means for causing a section of said bar to co-operate with needles of the other bar in the production 55 of rib fabric, means for causing the needles of another section thereof to knit plain fabric simultaneously therewith, and means for changing-over at will on one of said sections between rib and plain fabric, which said change-over means 60 comprises means for imparting differing pressing movements to said section to cause the long and short bearded needles to press simultaneously or separately.
12. A straight-bar rib knitting machine, having 65 a needle bar in which bearded needles alternate with dummies, an opposed needle bar in which long and short bearded needles alternate, the short bearded needles being opposite the dummies, means for knitting rib fabric on the needles 70 of the first bar and the long bearded needles of the second, which said means includes means for causing the short bearded needles to relinquish their loops without knitting them, and means for changing-over to plain fabric, which change- 75

- over means includes means for causing the needles of the first bar to relinquish their loops without knitting them and means for causing the short-bearded needles of the opposed bar to knit with the long-bearded needles.
13. A straight bar rib knitting machine, incorporating means whereby one can at will change from the production of rib fabric to the production of plain (non-rib) fabric, or vice versa, on a group of needles forming a portion only of the division of needles, and having means whereby rib fabric or plain fabric, as the case may be, can be simultaneously knitted on the remainder of said division.
14. A straight bar knitting machine, having means for knitting rib fabric on a group of the needles, means for simultaneously knitting plain fabric on a contiguous group, and means for

knitting one of these kinds of fabric on both groups.

15. A straight bar knitting machine incorporating bearded needles, a sectional needle bar, and means for moving the needle bar to press, having means for knitting either rib or plain fabric, and means for imparting differing pressing motions to at least a section of the needle bar according to whether rib or plain fabric is to be produced. 5

16. A straight bar knitting machine incorporating bearded needles, a sectional presser bar, and means for moving the presser bar to press the needles, having means for imparting differing pressing motions to at least a section of the presser bar according to whether rib or plain fabric is to be produced. 10 15

GEORGE TAYLOR.
